UNITED STATES PATENT OFFICE.

HERMAN WILHELM, OF NEW YORK, N. Y.

DESIGN FOR A BOUDOIR SLIPPER.

Application filed March 15, 1928. Serial No. 25,868. Term of patent 7 years.

To all whom it may concern:

Be it known that I, HERMAN WILHELM, a citizen of the United States, and a resident of the city of New York, in the county of New York and State of New York, have invented the new, original, and ornamental Design for a Boudoir Slipper, of which the following is a specification.

Reference is had to the accompanying drawings, in which—

Figure 1 is a plan view.

Fig. 2 is a side elevation of a boudoir slipper, showing my new design.

I claim:

The ornamental design for a boudoir slipper, substantially as shown.

Signed at New York in the county of Nassau and State of New York this 13th day of March, A. D. 1928.

HERMAN WILHELM.
